UNITED STATES PATENT OFFICE.

OTHNIEL B. EVANS, OF PHILADELPHIA, PENNSYLVANIA, ASSIGNOR OF
ONE-HALF TO AUGUSTUS HUNT, OF SAME PLACE.

WATER-CLOSET.

SPECIFICATION forming part of Letters Patent No. 284,544, dated September 4, 1883.

Application filed January 17, 1883. (No model.)

To all whom it may concern:

Be it known that I, OTHNIEL B. EVANS, a citizen of the United States, residing in the city and county of Philadelphia, State of Pennsylvania, have invented a new and useful Improvement in Water-Closets, which improvement is fully set forth in the following specification and accompanying drawings, in which—

10 Figure 1 is a top view of the portion of a water-closet embodying my invention. Fig. 2 is a side elevation thereof. Fig. 3 is a vertical section of a detached portion thereof.

Similar letters of reference indicate corresponding parts in the several figures.

15 My invention consists of means, substantially as hereinafter set forth, whereby the valve of a water-closet may be quickly and easily opened and closed and held tightly closed, provision being made for causing the valve to conform to any inequalities of the valve-seat.

20 It also consists of the construction of the joint of the collar and valve-chamber, said collar supporting the bowl and being supported on the valve-chamber, whereby escape of sewer-gas or vapors at said joint is prevented, said construction being hereinafter fully described.

25 30 Referring to the drawings, A represents a chamber, which is properly supported on a floor or elsewhere, and adapted to communicate with a sewer, cess-pool, or other place of deposit or discharge of water-closet matters.

35 B represents a collar, which is set on the top of the chamber A, and supports the bowl. (Shown in dotted lines.)

40 C represents a valve, which is located within the chamber A, and provided with ears a, to which is pivoted an arm, C', which is keyed or otherwise secured to a horizontally-arranged rotary shaft, D, whose bearings are on the sides of said chamber, said valve having its seat on the bottom of the collar B.

45 To one end of the shaft D is secured a spur-wheel, E, and with the same meshes a toothed segment, F, whose bearings are uprights, ears, or other suitable devices, those shown in the present case being uprights G; and said segment has secured to or formed with it a weight-

ed arm, H, to which is pivoted the handle or operating-lever J. (Shown in dotted lines.)

It will be seen that when the arm H is raised the segment F moves downwardly, thus rotating the wheel E, whereby the connected shaft D lowers and opens the valve C, whereby there is communication between the bowl and place of discharge. When the rod J is let go, the weighted arm H immediately restores the segment F to its normal position, in which operation said segment moves in an upward direction and rotates the wheel E, whereby the valve C is returned to its seat, thus closing the communication between the bowl and place of discharge, it being seen that the weighted arm H now causes the valve to press firmly and continuously on its seat, thus producing a tight joint between the parts, the valve, owing to its hinged connection with the arm C', readily conforming to any inequality of the face of the valve-seat.

It is evident that the wheel E may be of the form of a segment, and both wheel or segment E and segment F may be beveled; or of other suitable construction, the diameter of the wheel or segment E being less than that of the segment F, so that the motion of the valve in either direction is rapid, and the operation of opening the same accomplished with ease.

The top of the chamber A is flanged, as at 80 a' a'', and the collar B has the lower portion, which constitutes the seat, of reduced diameter, so as to be readily fitted into said chamber through its flanged top, the reduction or contraction of said chamber forming the shoulder or sustaining-seat b, which rests on the flange a. Packing c is interposed between the shoulder and flange, and screws or bolts d are passed through said shoulder and flange, whereby the collar and chamber are securely connected, and the packing is firmly compressed on the flange as a seat, thus providing a tight joint between the collar and chamber, through which the sewer-gas and vapors are prevented from escaping.

It will also be seen that the upper face of the shoulder b of the collar B supports the bowl, and the lower face thereof provides the surface for supporting the collar on the top of the chamber, it being noticed that the top, 95 100

bottom, and intermediate bend are of one piece of metal or material.

When it is required to reach the valve C, the shaft D, or the interior of the chamber A, the screws or bolts d are loosened, and the collar B may be raised from the chamber and entirely removed therefrom, thus exposing the valve, and permitting access to said valve and the chamber and other parts thereof, by which provision also the setting up of the valve and connections within the chamber may be readily accomplished.

In order that the chamber A may be sufficiently large at the side occupied by the shaft D to permit the motions of the valve C and valve C' without the necessity of widening said chamber, the flange a" is turned inwardly, it being noticed that the flange a' is turned outwardly, the two flanges firmly sustaining the collar B, the packing e being interposed between said sustaining-seat b and top of the chamber, as has been stated.

As the valve is adjusted by the weighted arm to hold a certain amount of water within the bowl as a seal, should water leak into the bowl the valve will drop, then discharge the surplus, and immediately afterward automatically close and tightly seat itself. In the event of back-pressure of water, &c., within the chamber A, the valve cannot open, and thus overflow of the bowl and escape of vapor, &c., therethrough is prevented.

Having thus described my invention, what I claim as new, and desire to secure by Letters Patent, is—

1. A chamber and valve-seat, in combination with a valve, C, and arm C', rotating shaft D, gear-wheel E, and the toothed segment F, having a weighted arm, H, said valve being pivoted to said arm, substantially as and for the purpose set forth.

2. A bowl-supporting collar provided with a valve-seat, and a discharge-chamber sustaining said collar, which projects thereinto, in combination with a valve, an operating-arm

hinged to said valve, a rotating shaft connected with said arm, gearing E F, weighted arm H, and handle-lever J, the wheel E being of less diameter than the segment F, substantially as and for the purpose set forth. 50

3. In a water-closet, a chamber and a valve-seat, in combination with a valve having ears a, the arm C', pivoted to said ears, the rotating shaft D, connected with said arm, the gearing E F, and weighted arm H, substantially 55 as and for the purpose set forth.

4. In a water-closet, a discharge-chamber with a flanged top, in combination with a bowl-supporting collar having a contracted part forming at its bottom a valve-seat, and above the same a bend or part forming a sustaining-seat for said collar on the chamber, the upper face of said bend sustaining the bowl, substantially as and for the purpose set forth. 60

5. In a water-closet, a valve, valve-seat, and an arm and rotary shaft connected with said valve, in combination with a bowl-supporting collar, and a discharge-chamber which supports said collar, having at top an outwardly-projecting flange, a', and an inwardly-projecting flange, a", substantially as and for the purpose set forth. 65

6. In a water-closet, a valve, valve-seat, and an arm and rotary shaft connected with said valve, in combination with a bowl-supporting collar, having a contracted part forming at bottom said valve-seat, and above the same a bend or part forming a sustaining-seat, and a discharge-chamber, which sustains said collar, contains the valve, and is formed at top with 70 a flange, on which the sustaining-seat of the collar is rested, packing being interposed between said flange and seat, the upper face of said bend sustaining the bowl, substantially as and for the purpose set forth. 75
